HARRY C. VOOTH, OF EAST HAVEN, CONNECTICUT, ASSIGNOR TO THE RATTAN MFG. CO., OF NEW HAVEN, CONNECTICUT, A CORPORATION

PORTABLE GARAGE LIGHT

Application filed April 29, 1929. Serial No. 358,790.

This invention relates to improvement in portable garage lights. These consist of a handle formed from wood or other electric-insulating material adapted to support an electric-light bulb connected with wires extending through the handle and with a cage mounted on the handle and surrounding the light-bulb so as to protect the same. In the more general construction of lamps of this character, difficulty is experienced in replacing the bulb when it is broken. The object of this invention is to provide simple and convenient means for connecting the cage to the handle, and the invention consists in the construction as hereinafter described and particularly recited in the claims.

In the accompanying drawings:

Fig. 1 is a side view of a portable garage light constructed in accordance with my invention;

Fig. 2 is an end view of the same;

Fig. 3 is a sectional view on the line 3—3 of Fig. 1, enlarged;

Fig. 4 is a side view partly in section of the handle illustrating the manner of connecting the guard thereto;

Fig. 5 is a perspective view of the handle detached; and

Fig. 6 is a perspective view of the handle-ring detached.

In carrying out my invention I employ a handle 10 formed from wood or other insulating material with an annular rib 11 at its outer end, this rib being formed with 35 notches 12, herein represented as three in number. The lamp-guard consists of a ring 13 formed on its inner edge with integral downwardly-extending arms 14 terminating in outwardly-extended fingers 15. These fingers correspond in number and location to the location of the notches 12 which they are adapted to enter, so that the ring will come to a bearing upon the outer edge of the rib 11.

45 A clamping-strap 16 is then placed around the handle, below the rib 11, and is of a width to engage at one edge with the rib and at the other edge with the fingers 15, the ends of the strap being secured together by a 50 screw 17 by which the ring 13 is firmly con-

nected to the handle. This ring has an upwardly band 18 struck inward on opposite sides to form projections 19 for the purpose as will hereinafter appear.

The cage proper is formed from wires 20 55 united to a head 21 and provided with a hook 28, the said wires being connected at their opposite ends with the flange 22 of a coupling-collar 23 which is formed on opposite sides with bayonet-slots 24 to engage 60 with the projections 19, whereby the cage is coupled with the handle. The bayonet-slots and projections, being on opposite sides, permit the cage to be readily engaged and disengaged with the handle when occasion requires, although the friction between the parts will be such as to firmly hold them connected together. However, in garage work these lamps are subjected to rough usage, and to prevent any possible disengagement 65 of the cage from the handle, I form a perforation 25 in the band 18 and registering-perforations 26 in the collar 23 through which a cotter-pin 27 may be entered so as to lock the band and collar against rotation and yet 70 permit the cage to be detached from the handle when necessary to replace the bulb.

In this construction the ring 13 is so firmly fixed to the handle that it is not liable to be disengaged therefrom, the device as a whole 75 being adapted to withstand the rough usage often imposed upon lamps in garage work.

I claim:

1. A portable garage light comprising a handle formed at its outer end with an annular rib having notches, a ring adapted to rest on said rib and formed with arms extending through said notches, said arms terminating in outwardly-extending fingers, a strap surrounding said arms and bearing upon said rib and fingers, means for connecting the ends of the said strap, said ring formed with an annular band provided with inward projections, and a cage provided with a collar adapted to be interlocked with the first-mentioned flange.

2. A portable garage light comprising a handle formed at its outer end with an annular rib having notches, a ring adapted to rest on said rib and formed with arms extending 100

through said notches, said arms terminating in outwardly-extending fingers, a strap surrounding said arms and bearing upon said rib and fingers, means for connecting the ends of the said strap, said ring formed with an annular band, and a cage provided with a collar, said band and collar being provided one with projections and the other with bayonet-slots to engage the same.

- 5 10 3. A portable garage light comprising a handle formed at its outer end with an annular rib having notches, a ring adapted to rest on said rib and formed with arms extending through said notches, said arms terminating in outwardly-extending fingers, a strap surrounding said arms and bearing upon said rib and fingers, means for connecting the ends of the said strap, said ring formed with an annular band, and a cage provided with a collar, said band and collar being provided one with projections and the other with bayonet-slots to engage the same, said band and collar also having aligned perforations and a cotter-pin entered therein.
- 15 20 25 In testimony whereof, I have signed this specification.

HARRY C. VOOTH.
